UNITED STATES PATENT OFFICE.

JAMES W. MARKHAM, OF EVANSVILLE, INDIANA.

SWITCH-OPERATING MECHANISM.

1,123,338.

Specification of Letters Patent.

Patented Jan. 5, 1915.

Application filed August 19, 1914. Serial No. 857,538.

To all whom it may concern:

Be it known that I, JAMES W. MARKHAM, a citizen of the United States, residing at Evansville, in the county of Vanderburg and State of Indiana, have invented a new 5 and useful Switch-Operating Mechanism, of which the following is a specification.

The present invention appertains to switch operating mechanism and aims to 10 provide a novel and improved appliance whereby the motorman of a street car, may throw the switch piece or tongue without leaving the car.

It is also within the scope of the invention, to provide a switch operating mechanism which will be improved generally in 15 its construction, to enhance the utility and efficiency thereof.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

The invention has been illustrated in its 30 preferred embodiment in the accompanying drawing, wherein:—

Figure 1 is a plan view of the track portion of the mechanism, parts being broken away. Fig. 2 is an enlarged sectional view 35 taken on the line 2—2 of Fig. 1 and illustrating the car and the portion of the operating mechanism carried thereby. Fig. 3 is an enlarged section taken on the line 3—3 of Fig. 1. Fig. 4 is an enlarged fragmental 40 longitudinal section of the car illustrating the portion of the actuating mechanism carried thereby.

In the drawing, the numeral 1 designates the main track from which the side track or 45 switch 2 is branched, the usual switch piece or tongue being designated by the numeral 3 and being mounted for oscillation in the usual manner. The present mechanism is employed for operating the switch piece or 50 tongue 3.

In carrying out the present invention, a longitudinal plate 4 is disposed between the rails of the main track 1 in advance of the side track or branch 2, and is provided with 55 the upturned flanges or ribs 5 along its side edges, the forward and rear ends of the

plate 4 and its flanges or ribs 5 being flared as at 6 and 7, respectively. The plate 4 is preferably mounted upon a case or housing 8 embedded within the road bed between the 60 rails.

A trip lever 9 is fulcrumed intermediate its ends upon the plate 4 midway between the flanges or ribs 5 of the said plate, the lever 9 being secured upon the upper end of 65 an upright rock shaft 10 which is journaled through the plate 4 and which projects into the case 8. The forward end of the lever 9 is pointed, as at 11, while the rear end of the lever is enlarged or flared, as at 12, to 70 swing snugly within the flared portion 7 of the plate 4. When the rear end or arm 12 of the trip lever 9 is swung against one side of the flared portion 7, the forward or pointed end 11 of the lever will rest against 75 the opposite rib or flange 5, as seen in Fig. 1, it being noted that the plate 4 and its ribs or flanges 5 form a channel in which the trip lever is pivoted for coöperation with the car-carried device as will hereinafter 80 appear.

The trip lever 9 is operatively connected to the switch piece or tongue 3 to throw the same, and to this end an arm 13 is secured to the rock shaft 10 within the case 8, and 85 a longitudinal reciprocatory rod 14 is pivoted to the arm 13 and extends to a point inside of the switch piece or tongue 3. The rod 14 is slidable through the case 8 and through a case or housing 15 disposed at 90 the inside of the switch piece or tongue 3.

In order to operatively connect the rear end of the rod 14 and the switch piece or tongue 3, a transverse rod 16 is slidable through an ear or lug 17 depending from 95 the switch piece or tongue 3, a nut or stop 18 being engaged upon the rod 16 to rest against the outer side of the ear or lug 17. A nut or seat member 19 is fixed upon the rod 16 between the switch piece 3 and the 100 rod 14, and a coiled wire expansion spring 20 is disposed upon the rod 16 between the ear or lug 17 and the nut 19, to hold the ear or lug 17 yieldably against the nut or stop 18. If desired, the rod 16 may be extended, 105 as at 21, to operate a signal or semaphore (not shown).

The inner end portion of the rod or bar 16 is provided with an aperture or slot 22 through which the rear end portion of the 110 rod 14 is engaged, the rear end portion of the rod 14, having an offset providing an

oblique or diagonal cam 23 which is slideable through the slot 22. The cam portion 23 is slideable through the slot 22 of the rod 16, whereby the reciprocation of the rod 14 will reciprocate the rod 16. When the rod 14 is slid forwardly, portion 23 will be moved completely through the slot 22 to the forward side of the rod 16, and the rod 16 will be positively locked against inward movement.

The car-carried device is attached to the front truck 24 and the car body 25, and embodies a vertical guide 26 attached to the truck 24 and having a lower bell or flared portion 27. A plunger 28 is slideable through the guide 26 and has pivoted to its lower end, a tappet 29 which is arranged to swing transversely within the beveled or flared portion 27. A pair of opposed leaf springs 30 are secured to the lower end of the guide 26 and bear against the opposite sides of the tappet 29 to hold the tappet in normal or neutral position. The guide 26 is so located that when the tappet 29 is depressed it will properly enter the channel 4-5 and coöperate with the trip lever 9 as the car approaches the switch.

The plunger 28 is arranged to be operated by the motorman, and to this end the guide 26 is provided with an arm 31 to which a bell crank lever 32 is fulcrumed, the lower arm of the lever 32 being operatively connected to the upper end of the plunger 28, and a draft rod or member 33 being pivoted to the upper arm of the receiver 32 and extending forwardly to a point underneath the front platform or motorman's cab. The forward end of the rod 33 is pivoted to a bell crank lever 34 fulcrumed to hanger 35 secured to the car body 25 and a thrust rod or plunger 36 is slideable through the floor or platform of the car body 25 and has its lower end pivoted to the lever 34. The thrust rod 36 is spring raised, to ordinarily raise the plunger 28 and tappet 29 carried thereby, in order that the tappet will not interfere with any objects upon the road bed. The thrust rod 36, however, may be readily depressed by the pressure of the motorman's foot, to depress the tappet 29 when it is desired to throw the switch piece or tongue 3 as the car approaches the switch.

In operation, assuming the rod 14 to be slid forwardly, as seen in Fig. 1, to thereby bring the trip lever to the full line position, and to bring the switch piece 3 to closed position, a car may then pass along the main track 1 without entering the branch or side track 2. As above indicated, the cam portion 23 of the rod 24 moves completely to the forward side of the rod 16, to hold the said rod against movement. Thus, when the rod 14 is moved forwardly, the rod 16 will be forced outwardly to bring the switch

piece or tongue 3 to closed position, it being noted, however, that the spring 20 enables the switch piece 3 to swing to open position when a car passes from the branch or side track 2 onto the main track 1. As soon as the switch piece 3 is released, it will return to closed position under the influence of the spring 20. When a car following the main track 1 and approaching the branch or side track 2, is to run onto the branch or side track, the motorman depresses the thrust rod 36 as the car approaches the switch, whereby the tappet 29 may be depressed to move snugly over the plate 4 and contact with and ride along that side of the lever 9 which is foremost. Thus, assuming the trip lever 9 to be in the position illustrated in Fig. 1, as the tappet 29 wips or rides along the side of the lever 9, and reaches the rear end or arm of the lever 9, the said trip lever will be thrown or swung to the dotted line position illustrated in Fig. 1. This will force the rod 14 rearwardly and will move the cam portion 23 thereof through the opening 22 of the rod 16, to thereby slide the rod 16 inwardly. As a result, the nut or stop 18 of the rod 16 bearing against the ear or lug 17 of the switch piece, will swing the switch piece inwardly, to thereby guide the car onto the branch or side track.

It is to be noted that the tappet 29 carried by the plunger 28 is held yieldably at neutral or intermediate position by the opposite springs 30, and the said springs enable the tappet 29 to swing laterally or to one side or the other, as it passes around the trip lever 29, and which will assist in throwing or swinging the trip lever from one position to the other. It is also to be noted that when the rod 14 is moved rearwardly to swing the switch piece 3 inwardly, the cam portion 23 will not move completely through the slot 22, and consequently when the car traverses the main track 1 from the left hand side of Fig. 1 to the right hand side, the switch piece 3 will be swung outwardly to closed position and the rod 16 engaging the cam portion 23 will move the rod 14 forwardly to again return the trip lever 9 to its practically normal position. However, if the switch piece 3 is left open, a car approaching the branch or side track 2 along the main track, may pass along the main track without entering the branch or side track, for the reason that the motorman may actuate the trip lever 9 by depressing the tappet 29. In other words, the car-carried device is operable for swinging the trip lever 9 in either direction when necessary.

With the present appliance, the motorman may readily throw the switch piece or tongue 3 when necessary, and without leaving the car.

The present apparatus is comparatively 130

simple and inexpensive in construction, may be readily installed, and is practical and efficient in its use.

Having thus described the invention, what is claimed is:—

In a switch operating mechanism, a switch piece, a transverse reciprocatory rod, the switch piece having a portion through which the said rod is slidable, a stop carried by the said rod and seatable against the outer side of the said portion of the switch piece, a spring carried by the said rod for yieldably holding the switch piece against the said stop, a trip lever, and a longitudinal reciprocatory rod operatively connected to the trip lever and having an offset portion providing a diagonal cam portion, the first

mentioned rod having a slot through which the said cam portion is movable to reciprocate the first mentioned rod, the cam portion being arranged to move completely through the first mentioned rod when the said rod is moved outwardly and being arranged to remain partially within the said slot when the first mentioned rod is moved inwardly.

In testimony that I claim the foregoing as my own, I have hereto affixed my signature in the presence of two witnesses.

JAMES W. MARKHAM.
